Primary Examiner — Derrick E Holland*Assistant Examiner* — Jennifer O King(74) *Attorney, Agent, or Firm* — Boardman & Clark LLP(57) **CLAIM**

The ornamental design for a battery module connector barrel, as shown and described in FIGS. 1-8.

DESCRIPTION

FIG. 1 is a back underside perspective view of a battery module connector barrel showing our new design;

FIG. 2 is a front overhead perspective view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front elevational view thereof; and,

FIG. 8 is a back elevational view thereof.

The broken lines shown represent portions of the battery module connector barrel that form no part of the claimed design. The dot-dash broken lines represent an unclaimed boundary between claimed and unclaimed surfaces. None of the broken lines form any part of the claimed design.
